UNITED STATES PATENT OFFICE.

WILLIS W. CASE, OF DENVER, COLORADO.

ASSAY-FURNACE.

No. 798,949.

Specification of Letters Patent.

Patented Sept. 5, 1905.

Application filed March 11, 1905. Serial No. 249,628.

To all whom it may concern:

Be it known that I, WILLIS W. CASE, a citizen of the United States, residing at Denver, in the county of Denver and State of Colorado, have invented certain new and useful Improvements in Assay-Furnaces; and I do hereby declare the following to be a full, clear, and exact description of the invention, such as will enable others skilled in the art to which it applies to make and use the same.

My invention relates to improvements in assay-furnaces; and the object of my invention is to provide a simple and economical furnace which may be used either as a crucible-furnace or as a muffle-furnace or as both combined, the design of the invention being that all the crucibles shall be heated up evenly and that all parts of the muffle shall also be heated up evenly at the same time, the difficulty in the two being that the crucibles next to the burner generally heat up faster than the other crucibles and that the rear end of the muffle is usually heated to a higher degree than the front or mouth of the muffle by reason of its having to be kept open part of the time to supply air for oxidizing purposes. By my invention these difficulties are completely removed, as will be hereinafter fully set forth.

With the objects stated in view my invention consists in the construction and combinations of parts, as hereinafter described and claimed.

In the accompanying drawings, Figure 1 is a top plan view of my improved furnace. Fig. 2 is a cross-section of the same on the line 2 2 of Fig. 1. Fig. 3 is a horizontal section of the same on the line 3 3 of Fig. 2. Figs. 4, 5, and 6 show modified forms of the parts used as combined supports and auxiliary heaters. Fig. 7 is a longitudinal section of my furnace as applied to a muffle alone, omitting the crucibles. Fig. 8 is a horizontal section of the same, taken on the line 8 8 of Fig. 9. Fig. 9 is a cross-section of the same, and Fig. 10 is a horizontal section of a modified form.

"a" represents the wall of the furnace, which is composed, as usual, of refractory material. This furnace is hollowed out inside for the reception of the crucibles and the muffle. The shape and working of the crucible part of my furnace is substantially the same as that set forth in an application of even date herewith, Serial No. 249,629. The interior part of the furnace, which is hollowed out for the reception of the crucibles, is practically in the shape of a rectangle for the reception of two rows of

crucibles which overlap each other. By the particular arrangement herein shown a greater number of crucibles can be used than has heretofore been the practice, as fully set forth in my said application of even date. The part of the furnace which receives the crucibles "b" is open at the top and is adapted to be closed by removable covers "c", as described in my said application. The sides of the wall are built in so as to fit around a part of the crucibles, as fully described in my said application. The muffle, which is practically of the usual shape, is contained in a second open space "d", which communicates with the open space "e", in which the crucibles are placed, the sole separation between said spaces being one of the side walls of the muffle itself, and at the top and the rear of this side where the muffle meets the wall of the furnace, as shown at "f", a lining of fire-clay is provided to prevent the gases from escaping through this point of union. The flame is admitted into the space "e" through the opening "g", "h" representing a burner for gas or liquid hydrocarbon of any usual or approved type. This opening "g" is near the bottom of the furnace and at one end thereof, as shown in Figs. 1 and 2, and the main portion of the flame is by its own force blown through to the forward part of the channel that is below and between the crucibles, although a portion of course plays up into the space between the crucibles. The left-hand row of crucibles and the end crucible of the right-hand row are supported upon a bench "i", cut away, as shown at "j", for the freer passage of the gases. Of the right-hand row of crucibles those nearest the burner are supported upon a solid bench "k" and those opposite the muffle, except the last one, are supported on a bridge "m", of which "l", Fig. 3, represents the abutment, the bridge being cut away to permit the passage of the flame and products of combustion on either side of the abutment "l". The muffle itself is supported upon separate pieces which are provided with projections or heaters, on which heaters the muffle rests and which heaters are highly heated by the passage around them of the gases. These projections are placed just as close together as is consistent with the proper circulation of the gases, the idea being that these projections will become highly heated, even to the point of incandescence, and will thereby act in the manner of a clean coke fire directly under the muffle itself to heat it. These projections may be of any desired shape

and of a volume of about one cubic inch each, or less for smaller work. These projections act as heaters, and by means of the construction described I have succeeded in quickly 5 and evenly heating up to a highly-satisfactory degree a muffle fourteen inches wide, eighteen inches long, and seven inches high—a feat which has never been accomplished before by the use of gas or hydrocarbon fuel, 10 the largest size of muffle hitherto used being ten inches wide by sixteen inches long and seven inches high, and that only slowly and with the greatest difficulty. In Fig. 6 is represented one form of these projections or supports. In Fig. 5 is represented another form, 15 and in Fig. 4 is represented a number of these projections *n*, separated from each other by channels *p* and by other channels *q*. A number of such pieces arranged side by side, each 20 provided with projections or heaters *n*, are shown in Fig. 2.

On the interior of the side wall of the furnace opposite to the crucibles and adjacent to one side of the muffle I form a number of ribs *r*, having spaces *s* between them. These 25 ribs and spaces gradually diminish in size from the mouth of the muffle toward the rear thereof in order to afford a freer passage for the gases near the mouth of the muffle, 30 where the cooling effect of the air entering the muffle is the greatest, so that the greatest portion of the heat is concentrated near the mouth of the muffle.

The sole exit for the gases of combustion 35 is the narrow annular opening *t* in the top of the furnace, which is at the top of a passage which is preferably enlarged toward the interior of the furnace and funnel-shaped, as 40 shown in Fig. 2, and within this opening is contained a cylindrical pipe *u*, which fits into a hole in the top of the muffle near its rear end. By reason of the fact that the gases of 45 combustion escape through a narrow annular opening around the discharge-pipe of the muffle a vacuum is created whereby the air on the ejector principle is drawn through the muffle, thereby creating and maintaining an oxidizing atmosphere within the muffle itself for cupeling and scorifying. By reason of 50 the large number of heaters and the arrangement of the ribs and passages in the wall of the furnace, as already described, the heat in the muffle is maintained at the desired degree and kept uniform from the mouth to the 55 rear notwithstanding the large amount of air passing through the muffle due to the ejector action of the burned gases.

One great difficulty hitherto encountered in the use of muffle-furnaces is that it has 60 been hard to maintain the proper oxidizing atmosphere and requisite heat for cupeling and scorifying, and before my invention it has been found necessary to use on all muffle-furnaces a discharge-pipe for creating a draft 65 through the muffle, either extending into the

open air or connected with the chimney. By my invention no such discharge-pipe is needed.

The action of the furnace is as follows: Flame from gas or liquid hydrocarbon is forcibly blown in through the burner *h*. By its 70 own force the major portion of the flame passes along underneath the crucibles, heating them as it passes, until it reaches the space opposite the muffle, where it divides, the major portion, however, going on beyond the 75 abutment *l*, both on account of the force of the blast and because the spaces *s* nearest the mouth of the muffle are the largest. This brings the greatest heat, so far as the muffle is concerned, at the mouth thereof, which is 80 greatly to be desired. The flame as it passes underneath the muffle not only heats up the muffle in the usual way, but the greater part of its heat which is not absorbed as it rushes past the refractory non-heat-conducting muffle 85 is intercepted by the projections or heaters *n*, which are heated to incandescence, and by radiation and conduction of great additional heat the entire muffle is heated to a very high uniform degree, the result being that both 90 the crucibles and the muffle are at the same time uniformly brought up to a working heat.

In the drawings I have represented eight crucibles. I wish it to be understood, however, that I can use a much greater number than 95 this, if desired, and in small furnaces a less number may be used. In one form of small furnace only four crucibles are used, and in that case the crucibles would be arranged directly opposite the muffle and the gases would be introduced in the direction indicated by the arrow *v* in Fig. 1.

In Figs. 7, 8, and 9 is shown a modified form of furnace in which the crucibles are omitted. In this case the flame is brought in through a 105 central channel 1, located considerably below the muffle itself. The flame enters at the rear of the furnace and is blown through the channel 1 toward the mouth of the muffle, which is supported on projections or heaters 2 and 4, 110 (resting on a base 3,) separated by channels running at right angles to each other, as already described. Immediately under the mouth of the muffle are arranged two cross-pieces or heaters of the type shown by Fig. 6, 115 one on each side of the channel 1, each piece consisting of a base and two upwardly-projecting walls 4, leaving a channel 5 between them and at each side for the purpose of directing the gases of combustion outward around the 120 mouth of the muffle, and these pieces act as larger heaters for the mouth of the muffle. Along the side walls of the furnace are arranged ribs 6, separated by spaces 7, which 125 spaces and ribs are largest near the mouth of the muffle and gradually diminish in size toward the rear. At the rearmost portion these may be omitted, if desired, as shown in Fig. 8, the construction being similar to that already described in connection with Figs. 1, 2, and 3. 130

The gases of combustion escape through a narrow annular slit 8, which surrounds an open cylindrical pipe 9, which is connected to the top and rear of the muffle. I do not restrict myself, however, to a cylindrical pipe, as a square pipe would answer the purpose.

In Fig. 10 is shown a modified form in which the flame instead of being admitted at the rear of the furnace is admitted at the side, as shown at 10. This form I use where the muffle is very wide in proportion to its length.

Having thus described my invention, what I claim as new, and desire to secure by Letters Patent of the United States, is—

15 1. In an assay-furnace, the combination with the walls thereof, of a muffle supported therein, means for supplying the major portion of the heat derived from the fuel around the mouth of the muffle and supplying it in lesser amounts toward the rear of the muffle, said means including heaters placed as closely together as is consistent with the circulation of the products of combustion, said heaters being adjacent to the muffle and heating the 25 same in the manner of a clean coke fire, substantially as described.

2. In an assay-furnace, the combination with the walls thereof, and a muffle supported within said walls, and means for heating 30 all parts of said muffle uniformly, comprising a large number of heaters placed as closely together as is consistent with the circulation of the products of combustion and located adjacent to said muffle, said walls being provided with ribs and passages diminishing in 35 size from the mouth of said muffle toward the rear thereof, substantially as described.

3. In an assay-furnace, the combination with the walls thereof hollowed out internally, of a series of crucibles and a muffle mounted in said furnace, one of the side walls of said muffle serving to divide the working space of said muffle from the crucible-containing space of the furnace, supports for said crucibles, and a large number of heaters arranged closely together located adjacent to said muffle, substantially as described.

4. In an assay-furnace, the combination of the walls thereof hollowed out internally, provided with an opening in the top for the escape of the gases of combustion, with an open-

ing near the bottom for the reception of a flame, and with an opening in the top for the insertion of crucibles, of a cover for said furnace, crucibles located in said furnace, supports for said crucibles, a muffle located in said furnace, one of the side walls of the muffle serving as a partition to separate the working space of the muffle from the crucible-containing space of the furnace, and means for 55 heating up said muffle evenly from the mouth to the rear, consisting of a large number of heaters arranged adjacent to said muffle, said wall being provided with ribs and passages diminishing in size from the mouth of the 60 muffle toward the rear thereof, substantially as described.

5. In an assay-furnace, the combination of the walls thereof and a top, said top being provided with a single escape-opening, a muffle 70 mounted in said furnace and provided with a discharge-pipe near its rear end, the passage surrounding said pipe for the escape of the products of combustion being annular in shape and surrounding the discharge-pipe of 75 the muffle, whereby the escape of the gases of combustion form a vacuum and act as an ejector draw the air through the muffle, thus producing an oxidizing atmosphere in the same, substantially as described.

6. In an assay-furnace, the combination with the walls thereof provided with ribs and passages of varying size, a muffle supported in said furnace, said furnace being provided with a single exit for the gases of combustion, and said muffle being provided with a discharge-pipe located centrally in said exit-opening, whereby the outrush of the gases of combustion causes a current of air through 85 said muffle, and means for maintaining a uniform heat from the mouth to the rear of said muffle, consisting of a large number of heaters arranged adjacent to said muffle and acting in connection with the ribs and passages already mentioned, substantially as described. 90

In testimony whereof I affix my signature in presence of two witnesses.

WILLIS W. CASE.
